CORYDON O. ORNE, OF SPRINGFIELD, MASSACHUSETTS.

METHOD OF ASSEMBLING THE PARTS OF KNITTING-MACHINE NEEDLES.

Application filed March 15, 1921. Serial No. 452,515.

To all whom it may concern:

Be it known that I, CORYDON O. ORNE, a citizen of the United States, residing at Springfield, in the county of Hampden and 5 State of Massachusetts, have invented certain new and useful Improvements in Methods of Assembling the Parts of Knitting-Machine Needles, of which the following is a specification.

- 10 This invention relates to an improved method of assembling knitting machine needles and likewise to an improvement in what is known as the screw rivet of such a needle, this being the part which pivotally connects the latch of the needle with the shank. In preparing the needle shank for the reception of such a rivet aligned holes are drilled through the walls of the latch slot in the needle shank and are tapped or 15 threaded. The screw rivet, which is, as stated above, the pivot for the latch comprises a shank of tool steel wire, cold drawn and annealed and threaded for a portion of its length, and up to the present time it has 20 been the custom to form the rivet blunt at its threaded or entering end. In drilling and tapping the holes for the reception of this rivet it almost invariably happens that a burr is formed about the ends of 25 the holes which open through the inner or opposing faces of the walls of the latch slot of the needle shank. These burrs, while almost imperceptible offer a serious impediment in assembling the needle parts 30 for notwithstanding their minute nature they partly close the respective rivet holes or openings. The outer end of each rivet hole or opening is usually formed with a countersink and no great difficulty is experienced in guiding and fitting the blunt 35 threaded end of the screw rivet into the outer end of the first opening through which it is to be passed, but after the rivet has been threaded through this opening its blunt end 40 meets with the obstruction offered by the burr at the inner end of the other or opposite opening and this end of the rivet is prevented from squarely entering the said opening. As a result, as the rivet continues to be 45 threaded through the first-mentioned opening, its blunt end will bear so forcibly against the opposite wall of the slot as to spring or bulge this wall in an outward direction and even should the blunt end of the 50 rivet enter the second opening, the needle is 55 so distorted as to be unfit for use and must be discarded or scrapped. As up to the step of assemblage the needle has been practically eighty per cent finished, the scrapping of a large number of needles, rendered necessary 60 by the difficulties encountered as above recited, means a considerable loss not only of time but also of material. The present invention, therefore, has as its primary object to devise a means whereby this difficulty 65 may be overcome and the consequent waste avoided, and as it is the presence of the burr at the inner ends of the rivet openings which is the prime cause of failure in assembling and producing a perfect needle, the invention 70 contemplates the automatic breaking down or removal of this burr at one step in the method of assembling the needle parts so that the threaded end of the screw rivet will as readily enter the second opening as 75 the first.
- Another object of the invention, in order to bring about the novel results mentioned above, is to provide a screw rivet of a novel form and which, as it is threaded into place, 80 will act as a reamer to break down or remove the burr at the inner end of the second opening entered by the needle.
- In the accompanying drawings—
- Figure 1 is a side elevation of a knitting machine needle of the ordinary type in which the latch is pivoted by a screw rivet formed and assembled in accordance with the principles of the present invention;
- Fig. 2 is a detail vertical transverse sectional view on the line 2—2 of Figure 1 illustrating the form of the rivet openings in the needle shank and also illustrating the screw rivet embodying the invention in position about to enter the first opening 90 through which it is to pass;
- Fig. 3 is a similar view illustrating the threaded portion of the shank of the screw rivet threaded through both of the openings in the needle shank and extending 95 freely through the opening in the latch;
- Fig. 4 is a similar view illustrating the next step in the method in which the surplus length is cut-off from the rivet;
- Fig. 5 is a similar view illustrating the 100 next step in which the stock, remaining after the step shown in Figure 4, is riveted down;
- Fig. 6 is a similar view illustrating a subsequent step in which the needle is completed;

Fig. 7 is a perspective view in detail of a screw rivet formed in accordance with the invention;

Fig. 8 is a view on a much enlarged scale 5 illustrating the difficulty encountered in the ordinary method of procedure when the ordinary rivet is employed.

In the drawings the numeral 1 indicates in 10 general an ordinary knitting machine needle, the shank 2 of which is formed with a latch slot 3 in which a latch 4 is to be pivotally mounted, in the manner shown in Figures 1, 3, 4, 5 and 6 of the drawings, by means of 15 the screw rivet and by the method of the present invention. In preparing the needle shank for the reception of the rivet the walls 20 of the slot 3 are drilled with aligned openings 6 which are tapped or threaded and which at their outer ends are flared or enlarged to provide countersinks 7. If reference 25 is now had to Figure 8, it will be observed, as somewhat exaggerated in said figure, that burrs are formed at the inner ends of the openings 6 during the tapping or threading operation, these burrs being indicated by the reference letter B. Figure 8 also represents a screw rivet of the ordinary type indicated by the letter R and this rivet is provided throughout a portion of its length 30 at one end with threads to match the threads of the openings 6, and at its threaded end is formed blunt. Inasmuch as the threaded end or extremity of the rivet R, although blunt, is of less diameter than the countersink 7 in 35 the first one of the openings 6 through which the rivet is to be threaded, no difficulty will be experienced in guiding the end of the rivet into this first opening and as the rivet is rotated or threaded through the opening 40 and its end passes beyond the inner end of the opening, the burr B, if any be present at this end of the said opening, will be pushed aside by the rivet. Thus far no difficulty has been experienced in threading the rivet 45 into place, but an obstacle is encountered when the rivet is further threaded through the first opening and its blunt end meets with the burr at the inner end of the other opening in the opposite wall of the slot for 50 this burr offers an obstruction which the blunt end of the rivet cannot pass except it be by the application of considerable force, and as a result this wall of the slot is liable to be bulged outwardly as represented by 55 the dotted lines in the said Figure 8, it being understood that up to this point the metal of which the needle shank is formed has not been tempered and is, therefore, relatively soft. As before stated, when a needle becomes 60 distorted in this manner it is unfit for use and must be discarded or scrapped with the result that all time and labor which has been expended in the formation of the needle up to this point is a total loss as well 65 as the material.

The screw rivet embodying the present invention is most clearly shown in Figure 7 of the drawings and is indicated in general by the numeral 8 and the said rivet comprises a short length of tool steel wire, cold drawn and annealed and threaded for a portion of its length at one end in the usual manner, as indicated by the numeral 9, so as to adapt it to be fit through the openings 6 in the walls of the latch slot. This rivet differs materially from the ordinary rivet, however, inasmuch as its threaded end is not formed blunt as is usually the case but is provided with a reaming point 10 formed preferably by cutting the extremity with opposite meeting bevels 11 which in the illustrated embodiment are two in number, although more than two bevels may be formed if it should be found desirable. It is immaterial how these bevels are produced and it may be done by a peculiar method of cutting off the rivet ends or by filing or dressing the ends.

It will now be evident that when a rivet formed in the manner above described is assembled with the needle shank in the usual manner, the reaming point of the rivet will readily enter the first opening through which the rivet is to be received and if a burr be present at the inner end of this opening, it is more than likely that the burr will be cut away rather than merely pushed aside as is the case where a blunt end rivet is employed so that at this point an advantage is gained inasmuch as, if the burr is removed more or less completely, it cannot offer any interference to the free pivotal movement of the latch which is supported upon the rivet as might happen if it were merely pushed aside or toward the middle of the latch slot. As the screw rivet is further threaded into place, its end 10 will meet the burr at the inner end of the second or other opening, if such burr be present, and due to the peculiar formation of its end, it will act as a reamer to cut away the burr and more or less completely remove the same before the extremity of the rivet actually reaches the inner end of the said second opening, and then, inasmuch as the burr has been removed, no obstruction is offered to the entrance of the said end of the rivet into the said second opening.

Having threaded the rivet through both openings in the manner and approximately to the extent shown in Figure 3 of the drawings, the surplus lengths which project beyond the outer faces of the shank of the needle are cut-off relatively close to the said faces and substantially as shown in Figure 4. The next step in the method consists in heading or riveting down the ends of the rivet in the condition shown in Figure 4 and as illustrated in Figure 5 and indicated by the numeral 12. In assembling the screw 120

rivet with the needle shank, the latch 4 has, of course, been placed in position and engaged by the said rivet, and after the completion of the step illustrated in Figure 5

5 the needle is ready for the hardening or tempering step which is usually followed at this point, the necessary minor grinding operations having been previously performed. The final step in the method consists in grinding down and polishing the side faces of the needle shank in which operation the riveted ends 12 of the screw rivet are brought flush with the said faces of the shank, as shown in Figure 6.

10 Having thus described the invention, what is claimed as new is:

1. The method of assembling the component parts of a knitting machine needle which comprises forming tapped openings in the 20 walls of the latch slot of such a needle, forming a threaded latch-pivot element with a reaming end, and fitting the said element through said openings and the latch, said end first, whereby to destroy any burr present at the openings.

2. The method of assembling the component parts of a knitting machine needle which comprises forming tapped openings in the 25 walls of the latch slot of such a needle, forming a threaded latch-pivot element with a reaming end, fitting the said element through said openings and the latch, said

end first, whereby to destroy any burr present at the openings, removing the surplus length of said pivot element, and heading the 35 ends thereof.

3. The method of assembling the component parts of a knitting machine needle which comprises forming tapped openings in the walls of the latch slot of such a needle, 40 forming a threaded latch-pivot element with a reaming end, fitting the said element through said openings and the latch, said end first, whereby to destroy any burr present at the openings, removing the surplus 45 length of said pivot element, heading the ends thereof, and removing the said headed ends flush with the surfaces of the needle.

4. The method of assembling the component parts of a knitting machine needle which comprises forming tapped openings in the walls of the latch slot of such a needle and providing said openings with countersinks at their relatively remote ends, forming a threaded latch-pivot element with a reaming end, fitting the said element through said 50 openings and the latch, said end first, whereby to destroy any burr present at the ends of the openings, cutting off the surplus projecting lengths of the said element, and heading the ends of the element in the counter- 55 sinks.

In testimony whereof I affix my signature.

CORYDON O. ORNE. [L. s.]
